UNITED STATES PATENT OFFICE.

VINTON E. SISSON, OF CHICAGO, ILLINOIS, ASSIGNOR TO WALTER P. MURPHY, OF CHICAGO, ILLINOIS.

END CONSTRUCTION FOR RAILWAY-CARS.

1,071,813.

Specification of Letters Patent.

Patented Sept. 2, 1913.

Application filed August 12, 1912. Serial No. 714,701.

To all whom it may concern:

Be it known that I, VINTON E. SISSON, a citizen of the United States, residing at Chicago, in the county of Cook and State 5 of Illinois, have invented certain new and useful Improvements in End Construction for Railway-Cars, of which the following is a specification.

My invention relates to the construction 10 of railway cars and particularly to the construction of box cars, and its object is to provide an all-metal end structure for box cars which will be very rigid and strong, so as to stand the shocks and stresses to 15 which the ends of railway cars are subjected, which furthermore will be simple and inexpensive, consisting of but few parts and which, finally, will be perfectly water-proof.

The invention consists in certain novel 20 arrangements, constructions and devices, to be hereinafter more fully described and claimed, for accomplishing the objects above stated and for, generally speaking, providing an improved all-metal end structure for 25 railway cars.

The invention is illustrated in a preferred embodiment in the accompanying drawings, wherein—

Figure 1 is an end elevation of a railway 30 car constructed in accordance with the invention; Fig. 2, a detail sectional view on an enlarged scale showing the devices and arrangements employed at the upper corners of the car; Fig. 3, a fragmentary plan 35 view of the end of the car with the roof sheets removed; Figs. 4 and 5, sectional plans taken on lines 4—4 and 5—5, respectively, of Fig. 1; Fig. 6, a vertical, sectional view taken on line 6—6 of Fig. 1, looking 40 in the direction of the arrows; Fig. 7, a fragmentary side elevation of one end of the car; Fig. 8, an end elevation of the upper portion of a box car showing a modified construction; Fig. 9, a plan view of this 45 construction with the roof's sheets removed; Fig. 10, a sectional view taken on line 10—10 of Fig. 8, looking in the direction of the arrows; and Fig. 11, a view in perspective of the upper portion of the end 50 sheet.

Like characters of reference designate like parts in the several figures of the drawings.

Referring first to Figs. 1 to 7 of the draw-

ings, 10 designates the side walls of the car, 55 11 the ridge pole, 12 the purlins, 13 the side plates, preferably angle irons, 14 nailing strips supported on the angle iron side plates 13, 15 the side fascia plates of the car, 16 the end fascia plates, 17 wooden roofing elements and 18 metal roofs sheets which are formed with flanges 19 which extend down over the side fascia plates 15 and the end fascia plates 16, respectively. Instead of the usual wood corner posts my improved 60 construction contemplates the use of angle bar end posts 20 which are turned with their angles outward as shown. The end of the car is composed of one or more sheets of metal. I have shown two such sheets, designated 21 and 22, provided with horizontally extending corrugations or strengthening ribs 23, the upper sheet 21 overlapping the lower sheet 22 and being secured thereto by the rivets 24. The vertically extending edges of 65 the sheet metal end lie within and against the transversely extending webs of the angle bar corner posts 20 and are secured thereto by the rivets 25. The upper end sheet 21 is formed at its upper edge with the inturned 70 flange 26 to which are riveted the triangular plates 27 secured to upstanding webs of the angle bar side plates 13 by means of angular gussets 28. The upstanding webs of 75 the side plates are preferably cut away to make room for the corner posts 20 and the gussets 28 riveted to the corner posts as well as to the side plates, as is best shown in Fig. 3. The side walls 10 terminate within the 80 corner posts as shown in Fig. 4. The lower end sheet 22 is formed at the bottom with the inturned flange 29 riveted to a plate 30 which rests upon and is secured to the channel formed end sill 31. 32 designates side 85 sills consisting of angle bars which are riveted to the corner posts 20 (Fig. 5). Gussets 33 are provided which are riveted to the side sills 32 and have angular flanges 34 similarly secured to the end sill 31 and to the corner posts. The structure at this point 90 95 may be further strengthened and rigidified by using the angular corner pieces 35 best shown in Figs. 1 and 5.

In Figs. 8 to 11, inclusive, I have shown a modified construction which is simpler and in some respects preferable to the construction above described. The upper end sheet 100 105 36 consists of a rectangular sheet of metal

with the top portions bent on the lines diagonal to the edges of the sheet so that in-turned flanges 37 are provided at the top of the plate which are roughly triangular in form, being wider at the outer edges of the sheet than at the middle. The diagonal lines on which the sheet is bent to form the flanges 37 correspond to the slope of the car roof from the ridge to the eaves. In this way an end sheet is made from a rectangular sheet of metal without the necessity of shearing. The flanges 37 support the ridge pole 38 and purlins 39 of the roof structure. The flanges are secured to the side plates 40 by angle iron gussets 41 which are also preferably riveted to the corner posts 42. The formation of the end sheet with the triangular flanges 37, in the construction last described, or the provision of the straight flange shown in the other construction with the triangular plates 27 constitute an important feature of the invention. The diagonal or weaving strains on the car are, of course, greater at the corners of the car than at the middle. The whole end structure of the car needs greater rigidity at the sides than it does at the center. This increased rigidity is provided by the gradual widening of the flanges 37, or by the triangular shape of the plates 27, which in the other construction constitute essentially a part of the flange on the end sheet. The spread of the flanges at their ends makes it possible to obtain a very rigid connection with the side wall structures of the car. When the end sheet is flanged as above described the ordinary end plate can be dispensed with. In fact the flanges serve all the purposes of trussed carlins sometimes used in place of or with the usual end plates.

While I have shown the invention as applied to a box car of a certain particular type, it will be readily understood that it is not to be considered as limited to all of the specific constructions and arrangements shown and described.

The invention provides a car end which is very strong and durable and which is particularly capable of withstanding the thrusts of the cargo, occurring when the train is stopped and started, which are so destructive to the wooden end structures commonly used. Furthermore, the structure is perfectly water-proof and is so designed that it will remain water-proof even after undergoing the hard usage to which railway cars under the best of circumstances are inevitably subjected.

I claim:

1. In a railway box car construction, the combination of corner posts, side plates, a sheet metal end having a flange at the top which is narrow at the middle of the car and

widens toward the sides, and means for securing said flange to the side plates. 65

2. In a railway box car construction, the combination of corner posts and side plates consisting of angle bars, a sheet metal end with a flange at the top which is narrow at the middle of the car and widens toward the sides, the vertically extending edges of said end being secured to the inner faces of said angle bars, and angular gussets securing the top flange to said side plates. 70

3. In a railway box car construction, the combination of corner posts and side sills consisting of angle bars, an end sill, a sheet metal end formed with an angular flange at the bottom and having its vertically extending edges secured to the inner faces of said angle bar corner posts, a plate secured to said bottom flange and resting upon and secured to the end sill, and gusset plates arranged in the corners of the car and secured to the end sill and side sills. 75 80

4. In a railway box car construction, the combination of angle bar corner posts disposed with the corners outward, side plates, side sills, and end sill, a sheet metal end provided with strengthening ribs and formed at the top and bottom with angular flanges, means for securing the top flange on the end to the side plates of the car, and means for securing the bottom flange on the end to the end sill. 90 95

5. In an end structure for railway cars comprising a rectangular sheet metal plate the upper portion of which is bent over on diagonal lines to correspond to the slope of a car roof from the ridge to the eaves and so as to provide flanges which increase in width toward the sides of the car, substantially as described. 100

6. The combination with the roof, side and wall structures of a railway box car, of a metal end structure comprising a sheet of metal the upper portions of which are bent over on diagonal lines to correspond with the slope of the car roof from the ridge to the eaves so as to provide a flange for supporting the roof structure which increases in width from the center of the car toward the sides, and means for securing said flange to the side wall structures of the car. 110

7. In a railway box car construction, the combination with the framing of a car, of a sheet metal end provided with an angular flange at the top which is narrow at the middle of the car and widens toward the sides, and means for securing said flange to the framing of the car. 115 120
